UNITED STATES PATENT OFFICE.

HENRY BAYER, OF SCHENECTADY, NEW YORK, ASSIGNOR TO GENERAL ELECTRIC COMPANY, A CORPORATION OF NEW YORK.

ELECTRIC SWITCH.

SPECIFICATION forming part of Letters Patent No. 729,255, dated May 26, 1903.

Application filed January 28, 1901. Serial No. 45,010. (No model.)

To all whom it may concern:

Be it known that I, HENRY BAYER, a citizen of the United States, residing at Schenectady, county of Schenectady, State of New York, have invented certain new and useful Improvements in Electric Switches, of which the following is a specification.

This invention relates to switches for electric circuits, and especially to incandescent lamp keys in which there is considerable lost motion between the make-and-break contact and its actuating-spindle, so as to permit a sudden opening of the lamp-circuit when the current is turned off, and thus reduce the 15 sparking.

So far as I am aware this class of switches has not heretofore been provided with means for suddenly closing the circuit instead of the comparatively slow closing occasioned by 20 the gradual and regular approach of the contacts. I find that sparking can be reduced and the life of the switch lengthened by so constructing it as to give a sudden closing movement in addition to the customary quick- 25 opening action.

My invention therefore consists in a switch in which there is a rotatable contact-block and means for giving it a sudden movement in closing, preferably in a direction trans- 30 verse to the axis of rotation. To this end I provide a polygonal contact-block with an oblong hole, by which it is loosely mounted on the spindle. A spring is arranged to exert a pressure on the block, so as to cause it to 35 move quickly in a lengthwise direction when turned to a predetermined position, and thus close the circuit with a sudden jump.

In the accompanying drawings, Figure 1 is a longitudinal sectional view of a lamp socket 40 and key embodying my invention. Fig. 2 is a sectional view of the same on a plane at right angles to Fig. 1 and with the outer shell removed. Fig. 3 is an end view of Fig. 1. Fig. 4 is an end view of the socket proper. Fig. 5 shows the make-and-break contact device, the several parts being separated. Figs. 6 to 45 9 show the several positions of the parts in closing the circuit. Fig. 10 is a perspective view of a modification on an enlarged scale.

The shell A and its insulating-lining B are of the usual construction. The screws C, 50

which fasten together the end and body of the shell, also enter recesses in the base D, of porcelain or the like, to which is secured the lamp-socket proper, E, being a screw-threaded metal shell having a bottom flange e, containing holes registering with holes d in the base to receive fastening-screws. The socket forms the contact for one of the lamp-terminals when the base of the lamp is screwed into 55 it. The other lamp-terminal bears against a center contact F, fastened to the base and carrying a binding-screw f for one of the line-terminals. A disk G, of mica or the like, lies between the center contact and the bottom 60 flange of the socket. The other line-terminal is connected to a binding-screw h on a U-shaped frame H, secured by a screw H' in a slot in the base D. In the arms of the frame is journaled the key-spindle I, having struck-up retaining-lugs i and provided at one end with a handle I' of insulation. The other end of the spindle has considerable play in its bearing h'. Just inside this end of the frame the spindle carries a contact-block K, preferably 70 75 an oblong rectangular piece of metal having an oblong recess in which are received the actuating-lugs i' on the spindle. The size of the recess is such as to leave sides k on each side as well as at the ends, thereby inclosing 80 the actuating-lugs, which in operating the block come in contact with said sides k. The block is thus stronger than those in which the lugs work in a transverse notch extending entirely across the block; but there is space 85 enough between the sides k and the lugs i' to afford a good deal of lost motion between the lugs and the block in order to give a "snap" action in opening the circuit, and thus obviate 90 sparking. A leaf-spring L is secured 95 to the frame, and its free end bears on the contact-block, forcing it toward the socket E.

The hole k' in the contact-block, through which the spindle passes, is oblong, so that the block can slip lengthwise in a direction 100 transverse to the axis of the spindle. This feature of construction results in allowing the block to slide suddenly into contact with the socket E when the key is turned to close the circuit. The operation is shown in detail in Figs. 6, 7, 8, and 9. As the block is turned from its open-circuit position in Fig.

6 to that shown in Fig. 7 the friction of the parts keeps the spindle at the left-hand end of the hole k' until the tension of the spring suddenly overcomes this friction and shoots 5 the block lengthwise, its corner striking the flange e of the socket E , as shown in Fig. 8. The circuit is thus closed instantly instead of by the comparatively slow approach of the block and flange due to turning the spindle. 10 In the modification shown in Fig. 10 the hole k' is enlarged at each end, so that the spindle will be retained therein for a longer time before the sudden movement of the block can take place. 15 The contact-blocks can be conveniently and cheaply made by stamping them up from a solid bar. 20 What I claim as new, and desire to secure by Letters Patent of the United States, is— 20 1. In an electric switch, the combination with a spindle, of a contact-block mounted loosely thereon, lugs on the spindle to rotate said block with lost motion, and a spring to move said block transversely with respect to 25 the spindle. 2. In an electric switch, the combination with the spindle having a side projection, of a rotatable contact-block having an oblong hole therein for frictional engagement with 30 the spindle and projection, and means for moving the block transversely on the spindle. 3. In an electric switch, the combination with the spindle having a side projection, of a rotatable contact-block having an oblong 35 hole therein for frictional engagement with

the spindle and projection, and a spring acting to move the block transversely with respect to the spindle.

4. In an electric switch, the combination with the spindle, of a contact-block having 40 an oblong recess in one side, said recess being inclosed on each side and end, and an elliptical aperture extending through the said block.

5. In a lamp-socket switch, the combination with the actuating-spindle having a side projection, of the switch-block having a slot for the reception of the spindle and projection and for frictional engagement therewith, and a spring which shoots the block transversely of the spindle when turned beyond the angle 45 of friction, to quickly close the switch.

6. In a lamp-socket switch, the combination with the actuating-spindle having lugs, of the switch-block having a slot for the lugs and a second slot for the spindle itself, and a spring 50 which shoots the block when permitted by the second slot, to quickly close the switch, and which shoots the block when permitted by the first slot, to quickly open the switch.

7. In an electric switch, the combination 55 with a rotatable actuator, of a switch-piece having a radial and circular lost-motion connection therewith, and a spring which quickly closes and opens the switch.

In witness whereof I have hereunto set my hand this 26th day of January, 1901.

HENRY BAYER.
